United States Patent Office

Des. 185,351
Patented June 2, 1959

185,351

LAZY SUSAN CONTAINER

Vladimir A. D'Arbeloff, Riverside, Conn.

Application September 25, 1958, Serial No. 52,765

Term of patent 14 years

(Cl. D58—11)

—Fig. 1

—Fig. 2

Fig. 3

Fig. 4

Fig. 1 is a top plan view of a Lazy Susan container, embodying my new design.

Fig. 2 is a side view of my new container with the cover in closed position.

Fig. 3 is a perspective view taken from the bottom and to the side with the cover in a raised position.

Fig. 4 is a perspective taken from the top and to one side with the cover in a base supporting position.

I claim:

The ornamental design for a Lazy Susan container, as shown and described.
